PLASTER MIXER

Austin K. Thomas and John W. Lendved, Wauwatosa, and Robert W. McKillop, South Milwaukee, Wis., assignors to Chain Belt Company, Milwaukee, Wis., a corporation of Wisconsin

Application July 28, 1954, Serial No. 31,644

Term of patent 14 years

(Cl. D14—3)

FIG. 1.

FIG. 2.

FIG. 3.

Fig. 1 is a view in perspective of a plaster mixer, embodying our new design, taken looking from the forward end along the discharge side thereof;

Fig. 2 is also a perspective view but taken looking from the other end more directly toward the discharge side of the plaster mixer and;

Fig. 3 is an other perspective view taken looking toward the opposite side thereof.

The dotted lines shown in Fig. 1 are for illustrative purposes only.

We claim:

The ornamental design for a plaster mixer, substantially as shown and described.
